SAMUEL C. McKEOWN, OF NEWARK, NEW JERSEY, ASSIGNOR TO SPLITDORF ELECTRICAL COMPANY, OF NEWARK, NEW JERSEY.

STARTER-COUPING.

1,360,963.

Specification of Letters Patent. Patented Nov. 30, 1920.

Application filed March 24, 1917. Serial No. 157,073.

To all whom it may concern:

Be it known that I, SAMUEL C. McKEOWN, a citizen of the United States, residing at Newark, in the county of Essex and State 5 of New Jersey, have invented certain new and useful Improvements in Starter-Couplings, of which the following is a specification.

My invention relates to a coupling device 10 to be used particularly in connection with internal combustion engines which, when being started, have a relatively low rotative speed at the time when the engine is going over compression, which is in general the 15 proper time for firing the gases in the engine cylinder and under this condition the spark produced by the magneto is rather weak and with the poor mixture usually obtained at this time starting is very difficult. As soon as the engine is started the 20 magneto renders ideal ignition and in order to overcome this objection, it has become the practice to accelerate the rate of speed of the magneto armature regardless of the slow 25 speed at which the engine is turned, thereby obtaining a spark substantially equal, and in most cases superior to the spark produced by the magneto when it and the engine is operated at high speed. In some types of 30 couplings used for this purpose no provision is made whatever for positively locking the driving and driven members of the coupling at its normal operating speed, dependence being placed on the strength of the impulse 35 spring for preventing any slip between the driving and driven members of the coupling. I am aware of two types of couplings which have the driving and driven members unyieldingly coupled together when the coupling 40 is stationary or not in use. Means are then provided for unlocking the driving and driven members of the coupling for the purpose of starting the engine. In these types of couplings the driving and driven members 45 are immediately locked after receiving one impulse and then must be unlocked again for the next succeeding impulse.

It is one of the objects of my invention to 50 simplify the locking features and to leave the driving and driven members normally unlocked for the purpose of generating consecutive impulses until a certain predetermined speed is reached which, in some cases, may be a little below the normal full load

running speed of the engine. By leaving 55 the driving and driven members of the coupling normally unlocked and only positively locking them at some speed higher than that required for starting, I do away with the wear and tear on the locking and 60 unlocking devices.

Another object of my invention is to provide a coupling which will perform its work in a noiseless and efficient manner, at the same time being relatively cheap to manufacture and easy to assemble. 65

In describing my invention I have utilized the type of coupling shown and described in Patent No. 1,226,933, issued May 22, 1917, to Fred B. Williams. 70

In the drawing, attached to and forming a part of this specification, Figure 1 illustrates a portion of an end view of a magneto having my improved type of coupling shown mounted on the end of the magneto shaft. 75

Fig. 2 is a view of the driven member of the coupling showing the buffer spring in place and the impulse spring in position of being assembled.

Fig. 3 is a view of the driving member as 80 it is taken off the driven member.

Fig. 4 is a rear view of the coupling shown in Fig. 1 with a small portion being shown in section.

Fig. 5 is a side elevation of Fig. 4, partly 85 in section.

Fig. 6 is an enlarged and sectional view of the locking feature shown in the small sectional portions of Figs. 4 and 5, but with the locking pin in its non-locking position. 90

Fig. 7 is a view of the spring shown in the small sectional portion of Fig. 4.

Fig. 8 is a modified form of a locking device. 95

Referring now particularly to the drawings, 1 is the end plate of a magneto having a shaft 2 on which is mounted the starter coupling, consisting of a driving member 3 and a driven member 4. The driving member 3 is provided with slots 5 in the 100 hub 6 for the purpose of receiving any suitable driving device, such as the end of an Oldham coupling. Within the driven member 4 is a spring 7 used for accelerating the rotative speed of the armature, all in a manner described in the said William's patent heretofore referred to. 8 is a buffer spring used to receive the shock of the 105

driven member when it overtakes the driving member after having been given an impulse by spring 7. 9 is a pin used for the purpose of assembling the spring 7.

5 No further description will be made of these parts as their functions are well understood.

In order to retard the driven member 4 so as to produce the necessary impulse a 10 pawl 10 is used which is carried on any suitable support 11 which may be attached to the base of the magneto. As shown in Fig. 1 the pawl is in position to retard the driven member 4, the end 12 thereof engaging a notch 13 in member 4. As the driving member 3 turns forward in the direction of the arrow a cam portion 14 engages the end 12 of pawl 10 throwing the same out of engagement with the driven member 4 allowing 15 the same to move rapidly forward under the impulse of the spring 7 as previously referred to. The cam surfaces 14 have holes 15 which will be referred to later.

Mounted on the back of the driven member 4 are two weighted arms 16 and 17 being pivoted to member 4 by suitable pivotal means, such as screws 18 and 19. As shown in Fig. 4 the weighted arms 16 and 17 are at their extreme outward positions resting 20 against the stops 20 and 21. When in their idle position these arms rest against the stops 22 and 23. Adjacent the pivotal points 18 and 19 are fulcrum edges 24 and 25 which are integral with the arms 17 and 16 respectively and between which extends a cross bar 26 loosely supported on the shaft 2. The object of this cross bar is to 25 preserve a balance between the two weighted arms 16 and 17. The arms 16 and 17 are 30 beveled at the point 27 adjacent the pins 28 which are also slightly beveled to coact with the bevel at the point 27 on the arms 16 and 17. The flange 29 of the driven member 4 is slotted at 30 and also has a counterbored 35 hole 31 within which is seated a screw 32. Mounted within the counterbored hole and surrounding the body of screw 32 is a specially formed resilient member 33 one end of which rests in the slot 30 and the other end passes through a hole 34 in the pin 28. The spring 33 acts to maintain the pins 28 in the position shown in Fig. 6. In starting the engine as the speed of the driven member increases the weighted arms 16 and 40 17 begin to move outward and toward the stops 20 and 21 and at a certain predetermined speed, which is below that speed at which the impulse spring 7 may start to cause a lagging action of the driven member due to its compression, they reach 45 these stops and at which time the pins 28 have been pushed inward, due to the engagement of the beveled surfaces on the members 16 and 17 and pins 28 so that the pins enter suitable receptacles 15 in the cam

surfaces of the driving member 3, thereby locking the driving and driven members unyieldingly together.

It will be understood that numerous changes and alterations may be made in the 70 various details of my invention without departing from the spirit of the invention or the scope of the appended claims, one of such changes being indicated in Fig. 8 in which the pin 35 is constructed differently 75 from the pin shown in Fig. 6 and a spiral compression spring 36 is used in place of the spring 33 shown in Fig. 7. The arrangement of the locking devices on both the driving and driven members may be also 80 varied over a considerable range of equivalents.

Having thus described my invention what I claim is:—

1. In a magneto attachment, a driving 85 member, a driven member, automatic coupling members consisting of pivotally mounted centrifugally operated arms carried by said driven member, a pin adapted to be acted on by said arms for unyieldingly connecting the two members but leaving said members normally uncoupled, means for arresting the movement of the driven member, means for releasing said driven member after a predetermined displacement of the 90 driving member, and resilient means for causing the driven member to overtake the driving member when the same is released, whereby the coupling means automatically locks the driven member to the driving member at a speed somewhat below the operating speed of the said members.

2. In a magneto attachment, a driving member, a driven member, automatic coupling members consisting of pivotally mounted centrifugally operated arms mounted on the rear surface of said driven member, a pin adapted to be acted on by said arms for unyieldingly connecting the two members but normally in such position 105 as to leave said members uncoupled, means for arresting the movement of the driven member, means for releasing said driven member after a predetermined displacement of the driving member, and means for causing the driven member to overtake the driving member when the same is released, said coupling members being responsive to the speed rotation of the driven member to lock 110 said driving and driven members, as described.

3. A starting coupling for igniter magnetos comprising co-axial relatively rotatable driving and driven members, a lock for positively holding said members against 125 relative rotation but normally spring-held in disconnected position, an actuating spring interposed between said members, a trip arranged to successively arrest said driven member to thereby place said spring under 130

tension and means for automatically shifting said trip to thereby release said driven member, said lock being operated by a plurality of pivotally mounted members responsive to centrifugal force.

4. A starting coupling for igniter magneto comprising co-axial relatively rotary driving and driven members, a spring interposed between said members in normal operative position, a shiftable trip arranged to successively arrest said driven member to thereby place said spring under tension and a cam lug on said driving member for shifting said trip to thereby release said driven member to permit said spring to move the driven member rapidly forward, a locking pin mounted in the driven member, a spring for holding the pin in unlocking position, means in the driving member to receive said locking pin and means responsive to centrifugal force for causing said pins to move into operative relation with said engaging means on the driven member at a predetermined speed.
5. In a magneto attachment, a driving member, a driven member, means for arresting the movement of the driven member, means for releasing said driven member after a predetermined displacement of the driving member and controlled by said driving member, and a spring for causing the driven member to overtake the driving member when the same is released, automatic coupling means mounted on said driven member for coupling said members together at a predetermined speed, said coupling means consisting of pivoted weighted arms responsive to centrifugal force, pins acted on by said arms and receptacles in the driv-

ing member for the reception of said pins 40 when acted on by said arms.

6. In a magneto attachment, a driving member, a driven member, automatic coupling means for unyieldingly connecting the two members but leaving said members normally uncoupled, means for arresting the movement of the driven member, means for releasing said driven member after a predetermined displacement of the driving member and resilient means for causing the driven member to overtake the driving member when the same is released, said coupling means consisting of a pair of pivotally weighted arms with a balancing member therebetween and pins adapted to be acted 45 on by said arms with receptacles in said driving member for said pins, and acted on at a predetermined speed of said members for locking the same positively together.

7. In a starter coupling for igniter magneto, the combination of driving and driven members with an actuating spring interposed between said members and means for imparting an accelerated rotary movement to said driven member, and means for locking said members positively together after said accelerated rotary movement has taken place, said locking means consisting of pivotally mounted centrifugally operated members and sliding members acted on by said 60 centrifugally operated members with receptacles in the driving member for said sliding members, and means for returning said pins and centrifugally operated members to their normal position when said igniter magneto is in stationary position.

In witness whereof I affix my signature.
SAMUEL C. McKEOWN.
